UNITED STATES PATENT OFFICE.

WILLIAM E. WRAGG, OF PHILADELPHIA, PENNSYLVANIA.

CONTROL FOR ELEVATOR-DOORS.

1,240,291.

Specification of Letters Patent. Patented Sept. 18, 1917.

Application filed December 16, 1916. Serial No. 137,348.

To all whom it may concern:

Be it known that I, WILLIAM E. WRAGG, a citizen of the United States, residing at Philadelphia, in the county of Philadelphia and State of Pennsylvania, have invented 5 certain new and useful Improvements in Controls for Elevator-Doors, of which the following is a specification.

My invention relates to improvements in 10 controls for elevator doors, the object of the invention being to provide improved means for opening elevator doors by the ascent or descent of the elevator, and permit the operator to position the operating 15 mechanism so as to pass a door without opening the same.

A further object is to provide improved 20 means carried by an elevator, adapted when in one position to cause the opening of the door when the elevator ascends or descends, and when in another position, permits the elevator to pass the door without opening.

It is to be understood that my invention 25 applies to that class of elevators in which doors or gates are provided at the different floors, which are designed to be opened automatically by the elevator in ascending or descending, and my invention consists in the provision of novel means for 30 controlling the operation of the doors, permitting such operation to be at the will of the elevator operator.

With these and other objects in view the invention consists in certain novel features 35 of construction and combinations and arrangements of parts as will be more fully hereinafter described and pointed out in the claims.

In the accompanying drawings:

40 Figure 1 is a fragmentary view showing a portion of an elevator and elevator shaft, and illustrating my improved means for controlling the opening of the door.

Fig. 2 is an enlarged view in section on 45 the line 2—2 of Fig. 1.

Fig. 3 is an enlarged fragmentary view in section on the line 3—3 of Fig. 1.

Fig. 4 is a view in elevation illustrating the door and its operating mechanism.

50 Fig. 5 is a fragmentary view in side elevation, illustrating the lever 20 and its adjacent parts.

Fig. 6 is an enlarged view in section on the line 6—6 of Fig. 5.

Fig. 7 is a similar view on the line 7—7 55 of Fig. 5, and

Fig. 8 is a fragmentary perspective view showing a fragment of the chain 15 to illustrate the manner of securing the lugs thereto. 60

1 represents an elevator door, and I would have it understood that I use this term "elevator door" to apply to such doors as are used at the floors or landings, which are a barrier to the elevator shaft, and do 65 not intend such term to apply to such doors as are carried by the elevator itself.

The door 1 is normally secured in its lower position by spring bolts 2, and branch cables 3 are secured to the door 1, and pass 70 through eyes 4 on the door, and also through eyes 5 on the bolts 2 so that when the cables are drawn taut in the act of elevating the door, they cause the bolts to unlock the door, and when the door closes, the slack in the 75 cable permits the spring bolts to lock.

The branch cables 3 are secured to an operating cable 6 which passes over idle pulleys 7 and 8, and is secured to an operating pulley 9. This pulley 9 is shown most clearly 80 in Fig. 3, and I would have it understood that the turning movement of the pulley 9 in either direction, causes the cable 6 to wind thereon and elevate the door 1.

Pulley 9 is secured to a shaft 10 supported in a frame 11, and on this shaft 10 a sprocket wheel 12 is also secured. A sprocket wheel 13 is supported by the frame 11, and an endless sprocket chain 15 is located around the sprocket wheels 12 and 13. 90 Two links 14 of the chain 15 are made in the form of laterally projecting plates, to which angular lugs 16 are secured.

17 represents an elevator, and 18 the cable controlling the movement thereof. A 95 vertical post 19 is secured to the elevator 17, and rigidly held in any approved manner. On the post 19, a sleeve 21 is mounted to turn, but is held against vertical movement by collars 22 secured on the post. The 100 rotary movement of sleeve 21 is limited by a pin 23 which projects through a slot 24 in the sleeve, and the turning movement of the sleeve is controlled by a lever 20, which is pivotally connected to a clamping collar 25 105 on the sleeve, and which may be positioned at either side of the pin 23 for a purpose which will hereinafter appear.

Weighted dogs 26 and 27 are pivotally connected to clamping collars 28 on the sleeve 21, adjacent their respective ends, and these dogs are adapted to engage the lugs 16, 5 and cause the door 1 to open when approached by the elevator.

It is of course to be understood, that the upper dog 26 causes the door to open when the elevator is moved upwardly, and the dog 10 27 causes the door to open when the elevator is moved downwardly.

When it is desired to pass a floor without opening the door, it is simply necessary for the operator to swing the lever 20 outwardly, 15 and then turn sleeve 21 to move the dogs 26 and 27 out of the path of lugs 16.

The lever 20 will fall by gravity and hold the sleeve against accidental turning movement. The dog 26 is so shaped that it will 20 pivot and pass the lugs 16, when the elevator is moved downwardly, and the dog 27 will pivot and pass the lugs 16 when the elevator is moved upwardly. The lugs are so positioned that the door 1 is opened just as the 25 elevator reaches the floor, and closes as soon as the elevator leaves the floor, as the movement of the chain 15 of the dogs causes the lugs 16 to ride around the curve of the sprocket wheels, and out of the path of the 30 dog so that the door can fall by gravity to closed and locked position.

Various slight changes may be made in the general form and arrangement of parts described without departing from my invention 35 and hence I do not limit myself to the precise details set forth, but consider myself at liberty to make such changes and alterations as fairly fall within the spirit and scope of the appended claims.

Having fully described my invention, what I claim as new and desire to secure by Letters Patent is:

1. The combination with a vertically movable door, and vertically movable lugs controlling the movement of the door, of an elevator, a member on the elevator having partial rotary movement, pivoted dogs carried by the member and adapted to engage the lugs, a fixed part, and a lever pivotally con-

nected to the member and adapted when in 50 one position to engage the fixed part and hold the member against movement, and adapted when moved to another position, to release the member and operate as a handle to permit movement of the member. 55

2. The combination with a vertically movable door and vertically movable lugs controlling the movement of the door, of an elevator, a vertical post secured to the elevator, a sleeve mounted on the post, dogs carried by 60 the sleeve and adapted to engage the lugs, and a member connected to the sleeve and adapted to move the same, and constructed to lock the same in different positions.

3. The combination with a vertically movable door, of an endless chain adapted when moved, to move the door, and lugs projecting from the chain, of an elevator, a vertical post secured to the elevator, a sleeve having limited turning movement on the post, a 65 pin on the post, a slot in the sleeve receiving the pin and limiting the turning movement of the sleeve, a lever pivotally connected to the sleeve and adapted to rest on either side of said pin, and pivoted dogs carried by the 70 sleeve adapted to engage the lugs and move the chain to open the door, when the elevator approaches the same.

4. The combination with an elevator door, a spring bolt normally holding the elevator 80 door in closed position, and having an eye thereon, an operating cable secured at one end to the door, an eye on the door, said cable passed through the eye of the bolt and through said last mentioned eye, and adapted when drawn taut to move the bolt from its locked position, an elevator, and means on the elevator for causing the movement of the cable to release the bolt and open the door. 90

In testimony whereof I have signed my name to this specification in the presence of two subscribing witnesses.

WILLIAM E. WRAGG.
